SIMULTANEOUS PRODUCTION OF VINYL-
AROMATIC COMPOUNDS AND ARYLACET-
YLENESRobert R. Dreisbach, Midland, Mich., assignor
to The Dow Chemical Company, Midland,
Mich., a corporation of MichiganNo Drawing. Application October 6, 1937,
Serial No. 167,598

5 Claims. (Cl. 260—168)

This invention concerns the simultaneous production of a vinyl aromatic compound and an arylacetylene by pyrolysis of a benzene derivative having the general formula

5

wherein R represents an isopropyl or isopropenyl radical, X and Y each represent hydrogen, halogen, or an alkyl radical containing not more than 3 carbon atoms, and n and n' are integers having a sum not exceeding 5. The invention particularly concerns the simultaneous production of styrene and phenylacetylene by pyrolysis of one or both of the compounds isopropyl benzene and alpha-methyl styrene.

Isopropyl benzene has heretofore been pyrolyzed at temperatures up to, but not exceeding 200° C., to obtain styrene and alpha-methyl styrene, but phenylacetylene has not been reported as a product of the reaction. In my own researches I have never obtained more than faint traces of phenylacetylene by pyrolyzing isopropyl benzene at such temperatures.

However, I have found that isopropyl benzene may satisfactorily be pyrolyzed at higher temperatures to obtain not only the usual products, styrene and alpha-methyl styrene, but also phenylacetylene in appreciable yield. In general, the yield of phenylacetylene becomes higher and that of alpha-methyl styrene lower as the pyrolysis temperature is raised and by the use of temperatures above 900° C. the formation of alpha-methyl styrene may practically be eliminated. I have also found that the styrene and phenylacetylene, which boil together, may readily be separated by distillation from any alpha-methyl styrene and unreacted isopropyl benzene present and that the alpha-methyl styrene, alone or admixed with isopropyl benzene, may be further pyrolyzed to produce additional styrene and phenylacetylene. The phenylacetylene serves as an effective agent for preventing polymerization 45 of the styrene, hence the mixture of these two compounds is a valuable and marketable product. When desired, the phenylacetylene may be separated from the styrene by the chemical treatments hereinafter described.

50 In order to obtain phenylacetylene in appreciable yield, the pyrolysis is conducted at temperatures above 750° C. and below that at which excessive carbonization occurs, preferably between 800° and 950° C. The pyrolysis may be carried out in any of the usual ways, e. g. by

passing isopropyl benzene alone or in admixture with a gaseous diluent such as steam or carbon dioxide through an externally heated tube or a bath of lead or other molten metal, but care must be taken to heat and promptly cool the vapors with sufficient rapidity to avoid excessive carbonization. In practice the pyrolysis is preferably carried out according to the general method for pyrolyzing alkylated aromatic hydrocarbons set forth in my co-pending application, Serial No. 151,457, filed July 1, 1937, of which this application is a continuation-in-part. This preferred mode of operation, described below, permits the desired products to be formed in higher yield than I have found possible by the usual pyrolytic methods, without appreciable carbonization or tarring of the reaction mixture.

In my preferred mode of operation, liquid or vaporized isopropyl benzene and superheated steam are passed continuously into admixture with one another, the steam being employed in the proportion and at the temperature required to attain the reaction temperature and furnish the heat of pyrolysis. Usually, between 7 and 10 parts by weight of steam superheated to a temperature between 800° and 1000° C. is used per part of isopropyl benzene, but the steam may of course be employed in other proportions and at even higher temperatures. The pyrolysis mixture is promptly cooled, e. g. by contact with water or passage through suitable heat exchangers or condensers, to a temperature below that at which rapid pyrolysis occurs, e. g. below 700° C., and the cooling is continued to condense the aromatic components of the mixture. The organic condensate is then distilled to collect as one fraction a mixture of styrene and phenylacetylene and as other fractions alpha-methyl styrene (when formed) and any unreacted isopropyl benzene. The alpha-methyl styrene may be collected as a final product or it may be returned, alone or in admixture with isopropyl benzene, to the pyrolysis for the formation of additional styrene and phenylacetylene.

As hereinbefore indicated, the phenylacetylene formed in the reaction distills together with the styrene and inhibits polymerization of the latter during manufacture, distillation, storage, and shipment. Accordingly, this mixture of styrene and phenylacetylene is a valuable product having properties not possessed by styrene alone. When desired, part or all of the phenylacetylene may be removed from the styrene either:—(1) by agitating the mixture at room temperature or there-

about with a mixture of mercuric oxide and a 30-50 per cent concentrated aqueous sulphuric acid solution to convert the phenylacetylene into other compounds readily separable from styrene 5 by distillation, or (2) by treating the mixture of styrene and phenylacetylene with an aqueous ammoniacal solution of a salt of a metal belonging to group 1, family 2, of the periodic system, e. g. silver chloride, silver sulphate, cuprous chloride, cuprous sulphate, etc., to precipitate the phenylacetylene as its metal salt, e. g. as silver or cuprous phenylacetylide. The ammoniacal metal salt employed in this treatment is preferably one containing the metal in its lowest 10 valence.

The first of said methods for removing phenylacetylene is simple and practicable, but does not permit recovery of the phenylacetylene as such.

After said treatment the styrene is separated and 20 purified by permitting the treated mixture to stand and stratify, separating the organic layer thereof, washing this layer free of acid with water or dilute aqueous alkali solution, and distilling the same, e. g. with steam or under vacuum.

25 The second of the above-mentioned methods for removing the phenylacetylene does permit recovery of the latter. After precipitating the phenylacetylene as its metal salt, the latter is separated by filtration or decantation to recover 30 the liquid styrene. The precipitate may then be acidified with a strong mineral acid, e. g. an aqueous sulphuric or hydrochloric acid solution, to regenerate the phenylacetylene. The latter forms a distinct layer and may be separated mechanically from the acid and purified by washing 35 with water. The invention, accordingly, permits production of styrene and phenylacetylene either in admixture or as the individual compounds.

The following examples illustrate certain ways 40 in which the principle of the invention has been applied, but are not to be construed as limiting the invention.

Example 1

45 Isopropylbenzene was passed, in continuous flow at a rate of approximately 50 grams per minute, first through a heated chamber wherein it was vaporized and preheated to about 285° C. and thence into admixture with a current of steam superheated to approximately 825° C., the 50 rate of steam flow being such that the mixture formed had a temperature of approximately 750° C. The vapor mixture was passed in less than 0.03 second through the mixing zone directly into condensers wherein it was rapidly cooled and 55 condensed. The organic layer of the condensate was separated and dried. It contained approximately 45.4 per cent by weight of unreacted isopropyl benzene, 27.3 per cent of styrene, 14.8 per cent of alpha-methyl styrene, and 0.43 per 60 cent of phenylacetylene.

Example 2

Isopropyl benzene was vaporized and preheated 65 to about 220° C. 24.2 pounds of the isopropyl benzene vapors and approximately 205 pounds of highly superheated steam were passed in steady flow through a tubular iron reactor, wherein they formed a mixture having a temperature of 805° C. The time of passage was 1 hour 20 minutes. 70 The mixture passed through the reactor and into suitable cooling apparatus at such rate as to be maintained at temperatures above 700° C. for less than 0.05 second, probably about 0.03 second. 75 The mixture was cooled as it issued from the re-

actor sufficiently to condense the aromatic products, leaving a gaseous mixture of hydrogen and lower aliphatic hydrocarbons. The organic layer of the condensate was separated and dried. It 10 consisted of 18.7 pounds of a mixture containing approximately 43 per cent by weight of styrene, 16 per cent of alpha-methyl styrene, and 4.3 per cent of phenylacetylene, the remainder being largely unreacted isopropyl benzene and some benzene.

Example 3

64.5 pounds of isopropyl benzene was gradually vaporized and the vapors were passed continuously into admixture with a stream of steam superheated to 890° C., the respective rates of 15 flow being such that the mixture had a temperature of about 825° C. The time of passage was 3 hours 30 minutes. The mixture was immediately cooled and condensed and the organic layer of the condensate was separated and dried as in Example 20 2. There was obtained 48.8 pounds of a liquid organic mixture containing approximately 52.8 per cent by weight of styrene, 9.3 per cent of alpha-methyl styrene, 8.5 per cent of phenylacetylene, and 12.5 per cent of unreacted isopropyl benzene, the remainder being largely benzene and 25 ethylbenzene. The yields of styrene, alpha-methyl styrene, and phenylacetylene were 52.6 per cent, 7.9 per cent, and 8.1 per cent, respectively, based on the isopropyl benzene consumed in 30 the reaction.

Example 4

Isopropyl benzene was vaporized and preheated to a temperature of about 440° C. and the preheated vapor was passed continuously into admixture with a stream of steam superheated to about 1070° C. at such rate that the temperature of the resultant mixture was approximately 900° C. The mixture was cooled and condensed immediately after formation and the organic layer of condensate was separated, dried, and analyzed. It contained 53 per cent by weight of styrene, 2 per cent of alpha-methyl styrene, and 8.3 per cent of phenylacetylene, the remainder being unreacted isopropyl benzene and by-products such as benzene and probably naphthalene.

Example 5

Meta-chloro-isopropyl benzene was pyrolyzed 50 at 820° C. by procedure similar to that in Example 3. The liquid organic product contained approximately 39 per cent by weight of meta-chloro-styrene, 5.1 per cent of meta-chloro-phenylacetylene, 3.9 percent of meta-chloro-alpha-methyl styrene, and 3.5 per cent of styrene, the remainder being largely unreacted meta-chloro-isopropyl benzene and some by-products such as chlorobenzene and meta-chloro-ethylbenzene.

I have also pyrolyzed meta-ethyl-isopropyl benzene as hereinbefore described to obtain a product comprising styrene homologues, e. g. meta-ethyl styrene, meta-divinyl benzene, etc., and arylacetylenes, e. g. phenylacetylene, meta-vinyl-phenylacetylene, etc. The arylacetylenes in the mixture inhibited polymerization of the styrene homologues. Other nuclear substituted isopropyl benzene compounds such as ortho-, meta-, or para-bromo-isopropyl benzene, 3-chloro-5-ethyl-isopropyl benzene, ortho-chloro-isopropyl benzene, para-methyl-isopropyl benzene, diethyl-isopropyl benzene, di-isopropyl benzene, etc. may be pyrolyzed according to the invention to obtain a product comprising homologues or analogues of styrene and an arylacetylene.

In the claims the term "styrene-like compound" refers to a compound of the class consisting of styrene and its homologues and analogues.

Other modes of applying the principle of the invention may be employed instead of those explained, change being made as regards the method herein disclosed, provided the step or steps stated by any of the following claims or the equivalent of such stated step or steps be employed.

10 I therefore particularly point out and distinctly claim as my invention:—

1. A method for the simultaneous formation of a styrene-like compound and an arylacetylene which comprises pyrolyzing at a temperature of 15 at least 750° C. a benzene derivative having the general formula

20 wherein R represents an isopropyl or isopropenyl radical, X and Y each represent hydrogen, halogen, or an alkyl radical containing not more than 3 carbon atoms, and n and n' are integers having a sum not exceeding 5.

25 2. A method for the simultaneous formation of a styrene-like compound and an arylacetylene which comprises heating to a pyrolyzing temperature of at least 750° C. and cooling sufficiently rapidly to avoid appreciable carbonization, a benzene derivative having the general formula

30 wherein R represents an isopropyl or isopropenyl

radical, X and Y each represent hydrogen, halogen, or an alkyl radical containing not more than 3 carbon atoms, and n and n' are integers having a sum not exceeding 3.

3. A method for the simultaneous production 5 of a styrene-like compound and an arylacetylene which comprises simultaneously passing separate streams of superheated steam and of a benzene derivative having the general formula

10 wherein R represents an isopropyl or isopropenyl radical, X and Y each represent hydrogen, halogen or an alkyl radical containing not more than 3 carbon atoms, and n and n' are integers having a sum not exceeding 5, into admixture to form a mixture having a temperature between 800° and 900° C. and promptly cooling the mixture to a temperature below 700° C., the steam employed being superheated sufficiently to attain said pyrolysis temperature.

15 4. A method for the simultaneous formation of styrene and phenylacetylene which comprises pyrolyzing isopropyl benzene at a temperature of at least 750° C.

20 5. A method for the simultaneous formation of styrene and phenylacetylene which comprises continuously passing isopropyl benzene into admixture with steam superheated sufficiently so that the mixture is formed at a pyrolyzing temperature between 800° and 950° C. and cooling the mixture to a temperature below 700° C. within 30 0.05 second after formation.

35 ROBERT R. DREISBACH.
